UNITED STATES PATENT OFFICE.

ALEXANDER BERNHARD DRÄGER, OF LUBECK, GERMANY.

SELF-CONTAINED BREATHING APPARATUS FOR USE IN NOXIOUS GASES.

Application filed June 9, 1921. Serial No. 476,238.

To all whom it may concern:

Be it known that I, ALEXANDER BERNHARD DRÄGER, a citizen of Germany, residing at Lübeck, Germany, have invented certain new and useful Improvements in Self-Contained Breathing Apparatus for Use in Noxious Gases, of which the following is a specification.

The invention relates to an apparatus for supplying respirable air to a person surrounded by irrespirable or poisonous gases or fumes, the apparatus being adapted to be carried or worn packwise on the back and enabling the person to enter and to stay at places having an atmosphere which is noxious.

The object of the invention is to produce a self-contained breathing apparatus arranged in the form of a pack which, while preserving a compact form, is exceedingly simple in construction, is efficient in use and fulfills all reasonable requirements in a better and more reliable degree than the known apparatus of the kind in question.

With this end in view the invention consists in certain novel features, combinations and arrangements of parts hereinafter fully described and particularly pointed out in the claims.

30 In the drawings:

Figure 1 is a diagrammatic view of the apparatus spread or extended flat on the ground.

Fig. 1^a is a detailed view of the hinge connection of the valve chest shown in Fig. 1.

Fig. 2 is an elevation on a larger scale of the pressure reducing valve and its high pressure oxygen supply pipe.

Fig. 3 is a horizontal section on the line P—Q of Fig. 2.

Fig. 4 is an elevation on an enlarged scale of a spring press-button valve controlling a by-pass conduit between the high pressure oxygen supply pipe and a suitable part of the air passage of the apparatus.

Fig. 5 is a vertical longitudinal section of the said spring press-button valve mechanism.

Figs. 6 and 7 are sectional views illustrating the means whereby the free ends of the admitting and discharging branches of the by-pass conduit are connected with the casting of the controlling press-button valve and the oxygen supply pipe and with the air passage of the apparatus.

Similar letters and numerals refer to similar parts throughout the several views.

Referring to Figure 1 the improved self-contained breathing apparatus comprises a mouthpiece *m*, a flexible exhaling pipe *e*, a breathing valve chest *v* connected by a flexible pipe *e*¹ and a branch pipe *e*² with the lower end of one or more air purifying cartridges or absorbers *a*. The upper ends of the latter are in communication with the valve chest by means of suitable flexible connecting piping *i*¹, while a flexible inhaling pipe *i* leads from said valve chest *v* to the mouthpiece. The apparatus further includes an oxygen containing cylinder *z* having a closing member or stop valve *z*¹ which admits oxygen through a pipe *d* to a pressure reducing valve *r*; the latter provides for the automatic flow of oxygen there through and through the pipe *r*¹ under reduced pressure into the said branch pipe *e*², that is to say, into the air circulation of the apparatus. A breathing bag *b* is connected to the valve chest *v* by a flexible pipe *b*¹ and a flexible by-pass conduit *c* (to be explained later on) extends between the oxygen supply pipe *d* and the supply pipe *r*¹. A spring press-button valve mechanism *p* is arranged at the reversing point of the said by-pass conduit, and a pressure gage *g* is mounted in connection with the high pressure branch of the by-pass conduit, preferably close to the press-button valve so that the wearer of the apparatus may at any time easily look at the said gage and ascertain, when the oxygen in the cylinder *z* is becoming exhausted.

The absorbers *a*, the branch pipe *e*² and the oxygen cylinder *z* are mounted on and securely fastened by any suitable means, such as buckle straps *f* and pipe clips *h*, to a supporting plate *k* provided with shoulder straps *s*. The supporting plate *k* has a lateral extension or arm *n* to the end of which is articulated the valve chest *v* preferably by means of a double hinge connection of well known construction, for example said hinge connection may comprise a plate *o* having eyes or lugs at its longitudinal edges, which lugs are pivoted by pins *o*¹ and *o*² to corresponding lugs of the arm *n* and the valve chest *v* (see Fig. 1^a). With this arrangement the chest *v* may yield under the influence of external forces and the like and swing either on the hinge pin *o*¹ or *o*², or on both.

The supporting plate *k* is provided at its sides with suitable leather straps *q*, *q'* or the like serving as a waist-belt for holding the said supporting plate in position close upon the body of the wearer of the apparatus. The by-pass conduit *e* and the breathing bag *b* may be suspended in any appropriate manner from the waist strap *q*, so that after the wearer has put on the apparatus press-button valve *p* and the pressure gage *g* are readily accessible and conveniently in view in front of the wearer's body somewhat on the left hand side, whilst the breathing bag is located at the side of the wearer and extends across or around his hip in which position the bag does not hamper the movement of the leg.

Owing to the lateral position of the valve chest it is possible to lead the breathing pipes up under the arm of the wearer to the breathing organs and consequently in a position where the same are least inconvenient. The pivotal attachment of the chest *v* renders it possible to adjust the chest and breathing pipes in any desired or into the most convenient position with relation to the wearer. The lateral and pivotal arrangement obtained by means of the hinge connection admits of a compact construction of the valve chest, as well as providing for convenient accessibility of the connecting or coupling means of the air conducting pipes at the valve chest. Furthermore, after disconnecting the couplings of the said pipes and removing the hinge pins the valve chest may be readily and easily removed as a whole or self-contained part of the apparatus for cleaning, repairing or replacing. As the couplings of the air conducting pipes at the valve chest are all in close proximity, they may, moreover, be covered by a common protecting leather apron wrapped around the valve chest in any suitable manner not shown in the drawing.

As it is obvious from Figure 1, the exhaled air the course of which to the absorbers *a* is indicated by winged arrows, traverses the said absorbers from below in an upward direction whilst the purified air the course of which to the mouthpiece *m* is shown by ordinary or unwinged arrows, escapes at the top of the absorbers. Owing to this arrangement a better utilization and effect of the carbonic acid absorbing power of the chemicals (such as caustic soda, caustic potash or the like) of the absorbers is obtained and at the same time the formation of moisture as well as the agglomerating and clinkering (glazing) of the chemicals is reduced.

As shown in Figures 2 and 3, the pipe or connection *d* which permits of the passage of high pressure oxygen from the oxygen cylinder *z* to the pressure reducing valve *r*, is provided at its side with a casing *9* in such a manner that the bores of the connection *d* and the casing *9* are situated at right angles to each other in different planes and some distance apart. The said two bores are in communication with each other by means of a small bore *d'* so that oxygen from the cylinder *z* may pass directly into the casing *9* without passing through the pressure reducing valve *r*. Practically the connection *d* and the casing *9* are made in one single piece to form a sort of cross-piece constituting a self-contained structure capable of being mounted and dismounted as a unit and at the same time avoiding the necessity for high pressure packings between the said two parts *d* and *9*. A stop-valve *10*, *11* operated by a hand lever *12* controls the passage of the oxygen through the casing *9*. Such stop-valves are well known and need no further description. In the operative position, the hand lever *12* is secured against unintentional turning by a suitable spring plate *13* attached to the casing of the pressure reducing valve *r* and embracing the said lever *12* with yielding pressure.

To the threaded end of the casing *9* (Fig. 7) is fastened, by means of a screw-cap *14*, a nipple *15* into the central bore *14'* of which is soldered or otherwise secured a high pressure pipe *16* which is coiled like a spring pipe around a wire rope *17* which serves as a supporting core. The end of said wire rope *17* is fastened in a suitable recess of a plug *18* whilst the high pressure pipe *16* is passed through a central bore of this plug. The latter is hard soldered at *19* to the end face of the nipple *15* and moreover is provided with a second bore or passage *20* having an outlet nipple *21* the purpose of which will be explained later on. The high pressure pipe *16* and its core *17* extend around the body of the wearer about to the front of the latter and their front ends are fastened in a similar plug *22* (Fig. 6) having an eccentric bore or passage *23* the purpose of which will be also explained later on. On the plug *22* which has a central bore *22'* is screwed a nipple *24* (Fig. 5) the central bore *24'* of which is in line with the central bore *22'*, and on the nipple *24* is screwed a casing *25*. The latter at the same time forms a support for the high-pressure gage *g* to the interior of which a radial bore *26* extending from the central bore *24'* of the nipple *24* is connected. On the free end of the nipple *24* which projects through the end wall of the casing *25*, is screwed a fixture *27* having two lugs *28* between which is pivoted a bell crank lever *29*, *29'*, the downwardly directed arm *29'* of said lever is provided with a suitable pad *30* or the like adapted to close or shut off the outlet of the bore *24'* under the pressure of the spring *31* acting against the horizontal arm *29* of the said bell crank lever. The latter is

covered and protected against external influences by a sealed cap 32 screwed upon the threaded end of the casing 25. The bell crank lever 29, 29^x may be operated to open the valve 30 by depressing a press button *p* which acts against the lever arm 29 and the pressure of the spring 31 located in a recess 34 of the fixture 27. The press-button is supported by an elastic membrane 35 suitably suspended in an aperture 36 of the wall of the cap 32, said aperture being surrounded with a protecting rim or flange 32^x. The interior of the cap 32 is in communication with the bore 23 of the plug 22 by way of a perforation 37 in the bottom of the casing 25 and an eccentric bore 38 of the nipple 24.

Over the high pressure pipe 16 and its supporting core 17 is pulled a flexible tube or hose *c* the ends of which are strapped or otherwise securely fastened to the plug 18 and casing 25 respectively (Figs. 6 and 7). With this arrangement a jacket *c*¹ is formed practically around the pipe 16 and core 17, which jacket is in communication with the bores 23 and 20 of the two end plugs 22 and 18. The outlet nipple 21 of the bore 20 is connected by means of a hose *r*² (Figs. 7 and 1) with the reduced pressure oxygen supply pipe *r*¹.

For the purpose of admitting additional oxygen into the air passage of the apparatus as desired or required in the event of an increased output of work on the part of the wearer of the apparatus, the wearer has but to exert a short finger-pressure upon the button *p* of the by-pass conduit and then to release it again. By this movement the lever 29, 29^x is rocked and the valve pad 30 lifted away from the outlet of the bore 24 (Fig. 5), so that a small jet of high pressure oxygen is permitted to pass from the supply pipe *d* through the spiral pipe 16 and the connections above described into the cap 32 whereby it will be reduced in pressure at the same time. Thence the reduced pressure oxygen takes its course through the bores 37, 38 and 23 into and through the hose *c*, through the bore 20, the outlet 21 and the hose *r*² into the supply pipe *r*¹ and thence into the branch pipe *c*², that is to say, into the air passage of the apparatus. The supply of additional oxygen by means of the by-pass conduit into the circulating system of the apparatus independently of the pressure reducing mechanism *r* may be effected as often as necessary by one or a plurality of successive pressure impulses on the button *p*.

It will be seen that under ordinary working conditions the bell crank lever 29, 29^x is under the pressure of its spring 31 and the outlet 24^x is closed or sealed by the valve 30, so that high pressure oxygen can not enter into the reduced pressure oxygen re-

turn branch of the by-pass conduit (Fig. 5). The forward branch of the by-pass conduit being constantly in communication with the interior of the oxygen container *z*, remains, however, filled up with high pressure oxygen, and as the pressure gage *g* is in constant communication with this forward branch, it will indicate the pressure or volume of the oxygen existing in the container at any time.

When it is desired or required for any reason to cut off the high pressure oxygen supply to the by-pass conduit, this may be done by simply turning down the hand lever 12 (Figs. 1 and 2) and screwing home the valve screw plug 10 against the bore 9 (Fig. 3).

I claim:

1. In a self-contained breathing apparatus of the kind described, the combination of a plurality of pipes, a fixture consisting of two integral sections extending transversely to each other and provided with bores extending at approximately right angles to each other in different planes and each connected with one of said pipes, said fixture further having a connecting channel extending between said bores to connect the same, and a valve in said fixture for controlling the communication between said bores.

2. In a self-contained breathing apparatus of the kind described, the combination of an oxygen container, a high pressure valve, a pressure gage, a fixture consisting of two integral sections extending transversely to each other in different planes and provided with bores extending at approximately right angles to each other in said different planes, said fixture further having a connecting channel extending transversely between and connecting said bores, a valve in said fixture for controlling the communication between said bores, connections from one of said bores to said oxygen container and pressure-reducing valve respectively, and a connection from the other bore to said pressure gage.

3. In a self-contained breathing apparatus, the combination of means for providing respirable air, a pressure-reducing valve connected with said means, a container for high pressure oxygen connected with said pressure-reducing valve, a by-pass conduit for said pressure-reducing valve, a pressure gage in continuous connection with said by-pass conduit, a cap extending over said by-pass conduit, a bell-crank lever mounted within said cap, a valve carried by said lever and controlling said by-pass conduit and a press-button for actuating said lever to operate said valve.

4. In a self-contained breathing apparatus, the combination of means for providing respirable air, a pressure-reducing valve connected with said means, a container for

- high pressure oxygen connected with said pressure-reducing valve, a by-pass tube connected with said means independently of said pressure-reducing valve, a fixture connected with the free end of said tube, a high pressure pipe connected with said oxygen container and extending lengthwise through said tube into connection with said fixture, a valve-seated bore in said fixture communicating with said high pressure pipe; an eccentric bore in said fixture communicating with said tube, a pressure gage carried by said fixture in constant communication with said high pressure pipe, a cap connected 10 with said fixture, a bell-crank lever within said cap, a valve carried by said lever and co-operating with said valve seat to control the communication between the two bores and between the high pressure pipe and said 15 by-pass tube, and a press-button mounted on said cap for actuating said bell-crank lever to operate said valve.
5. In a self-contained breathing apparatus, the combination of means for providing 20 respirable air, a pressure-reducing valve connected with said means, a container for high 25 pressure oxygen connected with said pressure-reducing valve, a by-pass tube connected with said means independently of said pressure-reducing valve, a fixture connected with the free end of said tube, a wire-supporting rope extending through said tube and connected with said fixture, a high pressure pipe connected with said oxygen container and coiled about said rope, 30 lengthwise of said tube into connection with said fixture, a valve-seated bore in said fixture communicating with said high pressure pipe, an eccentric bore in said fixture communicating with said tube, a pressure gage 35 carried by said fixture in constant communication with said high pressure pipe, a cap connected with said fixture, a bell-crank lever within said cap, a valve carried by said lever and co-operating with said valve seat to control the communication between the two bores and between the high pressure pipe and said by-pass tube, and a press-button mounted on said cap for actuating said bell-crank lever to operate said valve.

ALEXANDER BERNHARD DRÄGER.
